UNITED STATES PATENT OFFICE.

HAROLD JACKSON FISHER, OF HOTCHKISS, COLORADO.

HAY-RAKE.

No. 801,975.

Specification of Letters Patent.

Patented Oct. 17, 1905.

Application filed April 11, 1905. Serial No. 255,059.

To all whom it may concern:

Be it known that I, HAROLD JACKSON FISHER, a citizen of the United States, residing at Hotchkiss, in the county of Delta and State of Colorado, have invented new and useful Improvements in Hay-Rakes, of which the following is a specification.

This invention is a horse-rake characterized by improvements in the means for tripping the draft-dump.

The object of the invention is to enable the operator to work the rake successfully without removing his foot from the pedal which controls the trip.

15 A further object is to provide means for holding the teeth to the ground without effort by the operator.

20 A further object is to form improved means for engaging and disengaging the pawl and ratchet which operates the dump.

The invention is illustrated in the accompanying drawings, in which—

Figure 1 is a plan view of a rake provided with my improvement. Fig. 2 is a vertical 25 sectional view showing the position of the parts before the dump is tripped. Fig. 3 is a similar view showing the position of the parts after the dump is tripped. Fig. 4 is a detail in plan, partly in section, showing an adjustable stop and associated parts. Fig. 5 is a section on the line 5 5 of Fig. 4. Fig. 6 is a detail, partly in section, showing the manner of attaching the rake-head to the other axles. Fig. 7 is a detail in elevation, showing the 35 latch-link and its detent. Fig. 8 is a detail in plan of the treadle and parts carried thereby.

Referring specifically to the drawings, 6 indicates the short wheel-axles, having thereon wheels the hubs of which carry the ratchets 40 7. 8 is a rake-head secured at the ends to said axles and mounted to rock thereon and having secured thereto the teeth 9. The head has a projecting arm 10, connected to a slotted link 11, having at its lower edge a series of 45 forwardly-presented notches 12 and at the upper edge of the slot a series of backwardly-presented notches 13. The link works through a guide-loop 11^a, supported on the frame of the rake.

50 14 indicates a bar extending along the upper side of the rake-head and having at the ends pawls 15, arranged to engage the ratchets 7.

55 16 indicates a pedal pivoted at the top of a bracket 17, supported on the frame 18 of the rake, and this pedal has extending from one

side thereof a cranked rod 19, which projects into the slot in the link 11 in position to engage in the notches 13.

20 indicates a stop-pin projecting from the 60 side of the pedal 16 in position to support the crank 19 when it swings back.

At 12^a is indicated a detent secured to the frame and arranged to engage in one of the notches 12. 65

Depending from the pedal is an arm 21, connected to a rod 22, which works through a guide 23 and hole in the upturned flange of the angle-iron frame of the machine in position to strike the lower end of a metal spring- 70 arm 24, which is secured at its upper end to the rocking bar 14.

25 indicates a segmental bracket corresponding in curvature to the movement of the arm 24 when the rake is dumped and carrying 75 an adjustable stop 26 in position to strike the end of said arm 24. The rocking bar 14 has a counterweight 27, tending to disengage the pawl 15 from the ratchet-wheel.

In operation the rake is normally dropped 80 and held down by engagement of the detent 12^a in one of the notches 12. When it is desired to dump the rake, the pedal 16 is tipped downwardly and forwardly. This turns the crank 19 and lifts the link 11 out of engagement with the detent 12^a. At the same time it pushes back the rod 22, which strikes the lower end of the arm 24 and rocks the bar 14 so that the pawls 15 engage in the teeth of the ratchets 7. The effect of this is to couple 90 the ratchet and rake-head and swing the latter forwardly to dump the rake, the link 11 sliding forwardly through the guide 11^a. When the arm 24 strikes the stop, the movement of the pawl with the ratchet is arrested 95 and the pawl is turned out or back and disengaged from the ratchet, which allows the rake to drop to the ground. As the link 11 slides back one of the notches 13 catches the crank 19 and pulls it back to its original position, at which time one of the notches 12 will engage the detent 12^a. A series of notches 100 13 are made, because the dump may be adjusted to rise to various heights, and if there were but one notch the link might not slide far enough forward to fall into engagement 105 with the crank 19.

What I claim as new, and desire to secure by Letters Patent, is—

1. In a horse-rake, the combination with an 110 axle, a wheel-operated ratchet thereon, and a rake-head carrying a pawl arranged to engage

the ratchet, of an arm connected to the pawl and depending below the rake-head, a treadle having a push-rod arranged to strike the arm and throw the pawl in engagement with the 5 ratchet, and a bracket secured to the frame of the rake and extending under the rake-head adjacent said arm and carrying an adjustable stop located in the path of the arm, to stop the same and disengage the pawl.

10 2. In a horse-rake, in combination, a wheel-axle, a rake-head mounted thereon, means to engage the latter with the wheel to dump the rake, a slotted link connected to the rake-head and having notches, a detent engaging in one 15 of the notches when the rake is dropped, and a treadle having a swinging projection working in the slot and arranged to lift and disengage the link when the treadle is depressed.

3. In a horse-rake, the combination with a 20 rake-head and wheeled axle, and pawl-and-ratchet mechanism to connect the head and wheels to dump the rake, of a notched latch-

link connected to the rake-head, a detent on the frame engageable in a notch of the link, and a treadle having a swinging projection 25 engaging the link to lift and unlatch the same when the treadle is depressed, and also having means to actuate the pawl to simultaneously engage the ratchet.

4. In a horse-rake having draft-dumping 30 means, the combination of a rake-head, a slotted latch-link connected thereto and having notches on its lower edge engaging a detent, and a treadle having a cranked rod extending into the slot to lift the link when the treadle 35 is depressed.

In testimony whereof I have signed my name to this specification in the presence of two, subscribing witnesses.

HAROLD JACKSON FISHER.
